Allen P. Algier, Los Angeles, Calif., assignor of
one-half to Ford Radenbaugh, Los Angeles,
Calif.

Application November 21, 1949, Serial No. 6,167

Term of patent 7 years

(Cl. D31—4)

To all whom it may concern:

Be it known that I, Allen P. Algier, a citizen of the United States of America, residing in the city of Los Angeles, in the county of Los Angeles, State of California, have invented a new, original, and ornamental Design for a Fish Lure, of which the following is a specification, reference being had to the accompanying drawing, forming a part thereof.

Fig. 1 is a side elevational view of a fish lure, showing my new design;

Fig. 2 is a top plan view;

Fig. 3 is a bottom plan view;

Fig. 4 is a view taken from the head end of the lure;

Fig. 5 is a view taken from the tail end of the lure; and

Fig. 6 is a cross-section taken on the line 6—6 of Fig. 1.

I claim:

The ornamental design for a fish lure, substantially as shown.

ALLEN P. ALGIER.
